Primary Examiner — Melanie Pellegrini*(74) Attorney, Agent, or Firm* — The Concept Law Group, PA; Scott D. Smiley; Scott M. Garrett**CLAIM**

The ornamental design for a striped watch band, as shown and described.

DESCRIPTION

FIG. 1 is a front and right side perspective view of a striped watch band in accordance with the present invention;

FIG. 2 is a front elevational view thereof;

FIG. 3 is a top plan view thereof; and,

FIG. 4 is a bottom plan view thereof.

The broken line showing of a watch case represents environment. The broken lines shown on the watch band represent portions of the striped watch band which form no part of the claimed design.
